[57] CLAIM

The ornamental design for a stop for windows, doors and the like, substantially as shown.

DESCRIPTION

FIG. 1 is a front perspective view of a stop for windows, doors and the like showing my new design;

FIG. 2 is a rear view thereof;

FIG. 3 is a side elevational view thereof;

FIG. 4 is an end elevational view thereof;

FIG. 5 is an end view opposite from the end shown in

FIG. 4; and

FIG. 6 is a bottom plan view thereof.
